UNITED STATES PATENT OFFICE

AUGUST GRAMS, OF NEWARK, NEW JERSEY

FOLDING CHAIR

Application filed August 31, 1928. Serial No. 303,144.

This invention relates, generally, to improvements in folding chairs; and the same has for its principal object to provide, in combination, a seat portion with foldable support and a foldable back portion, the parts being so devised and mutually interconnected that they may be easily and quickly folded up or opened out as desired, and, furthermore, the arrangement and relation 10 of the parts being such that the inclination of the back portion relative to the seat portion, when the chair is opened out, may be selectively adjusted to various angles.

The invention has for a further object to provide a folding chair construction which, although strong and durable nevertheless is exceedingly light in weight; which may be collapsed into a very compact condition when folded up; and which possesses an arrangement and construction of flexible seat and back webs which may be easily dismounted from their supporting frame structures for cleansing or renewal.

Other objects of this invention, not at this time more particularly enumerated, will be clearly understood from the following detailed description of the same.

The invention is illustrated in the accompanying drawings, in which:—

Fig. 1 is a side view of the novel folding chair, made according to and embodying the principles of this invention, as opened out to or set up in an operative or service condition; Fig. 2 is a front elevation of the same; Fig. 4 is a top or plan view of the same; and Fig. 3 is a vertical longitudinal section through the same.

Fig. 5 is a side elevation and Fig. 6 is a front elevation of the novel folding chair collapsed to folded up condition.

Fig. 7 is an enlarged fragmentary side elevation showing the interlocking connection between the back frame and seat supporting frame, when the chair is set up in service condition; and Fig. 8 is another view of said parts looking toward the left in Fig. 7.

Similar characters of reference are employed in all of the herein above described views, to indicate corresponding parts.

Referring now to said drawings, the chair

seat supporting frame comprises pairs of front legs 10 and rear legs 11 pivotally connected together at their central portions so as to provide crossed or X-shaped supports at each side of the chair structure. The respective pairs of legs 10—11 thus provided are laterally spaced by a central pivot bar or rung 12, the pivoting screws 13 of the legs 10—11 being secured in the ends of said central pivot bar or rung 12, or such other type of pivotal connection thereof with the ends of the latter as may be desirable may be employed. The legs 10 and 11 are preferably made metal bars, since such material affords adequate strength and durability while at the same time being of minimum bulk or thickness. The lower extremities of the front legs 10 are interconnected by a footing rung 14, and, in like manner, the lower extremities of the rear legs 11 are interconnected by a footing rung 15. The footing rungs 14 and 15 may be attached to the said legs by fastening screws 16, or any other suitable form of fastening means. Said footing rungs 14—15 provide a substantial bearing or footing contact with the surface upon which the chair stands, and permit of the chair being adequately and firmly supported even on soft soil or sand, thus enabling the chair to be satisfactorily used as a beach chair and for other out-door use.

The upper extremities of the front legs 10 are interconnected by a lateral seat supporting bar 17, and, in like manner, the upper extremities of the rear legs 11 are interconnected by a similar lateral seat supporting bar 18. The said bars 17—18 are preferably of cylindrical form, and the same are removably or detachably assembled in operative extension between said leg portions by suitable fastening devices, such as the screws 19, which extend through the leg portions and into the ends of the bars. For purposes to be subsequently disclosed, the fastening devices which connect the bar 17 with and between the upper extremities of the legs 10, are arranged to project exteriorly beyond the exterior faces of the legs 10 so as to furnish external stud or stop portions 19' (see Figs. 7 and 8).

The reference character 20 indicates a flexible seat member. This seat member may be made of canvas, leather or any other flexible material, and the same is provided respectively at its front and rear marginal portions with attachment loops or sleeves 21 and 22 which may be respectively engaged over the supporting bars 18 and 17. It will be obvious, that, by disengaging the fastening screws 19, the supporting bars 18 and 17 may be removed from the seat supporting frame structure, whereby the seat member 20 may be detached from the bars 18 and 17 either for cleansing or replacement.

The back portions of the chair comprises a pair of side uprights 23 which are pivotally attached at their lower end portions to the rear legs 11 at points intermediate the foot portions and the pivotal connection of said rear legs with the front legs 10, so as to extend upwardly at the sides of said chair seat portion. Said side uprights 23 are preferably produced from metal bars adapted to afford adequate strength and durability with a minimum of bulk. The upper extremities of said side uprights 23 are interconnected together by a top rung 24 and also by a second rung 25 at points above and adjacent to the seat member 20, said rungs 24 and 25 being suitably secured to the side uprights by screws 26 or other suitable fastening means. Formed in the rear marginal portion of each side upright is a locking notch or indentation 27.

The rear leg members 11 are provided with a plurality of spaced perforations 28, or the lower end portions of said side uprights 23 are provided with a plurality of spaced perforations 29, or both sets of perforations 28 and 29 may be furnished, all whereby the pivoted ends of said side uprights 23 may be variously adjusted by locating the pivot bolts 30 in and through selectively registered perforations 28 and 29 to thereby selectively determine the position of the locking notch or indentation 27 so that the inclination of the chair back portion relative to the seat portion, when the chair is set up, may be selectively varied, within certain limits.

The reference character 31 indicates a back member. This back member may be made of canvas, leather, or any other suitable material; and, preferably, comprises a sleeve like structure which may be telescopically slid over the chair back portion so as to be spread across and between the side uprights 23. It will thus be obvious that the back member 31 may be removed at will from the back portion either for cleansing or replacement.

To open up the chair, the legs 10 and 11 are turned on their pivotal connections to opened out X-shape, thereby spreading the upper portions apart to stretch the seat member 20 into operative horizontal extension

therebetween, while at the same time spreading apart the lower portions (with their foot rungs 14-15) to chair supporting positions. At the same time the back portion is swung rearwardly on its pivotal connection, until the locking notches 27 are engaged with 70 and over the external stud or stop portions 19' and the upper ends of the legs 10, thereby positioning and holding the chair back portion in operative service relation to the seat portion. 75

To collapse the chair to folded position, the back portion is released from engaged relation to the studs 19' and swung to a substantially vertical position, whereupon the legs 80 10-11 are swung together on their pivotal connections with their upper portions respectively disposed on opposite sides of the back portion, and with the seat member 20 depending therefrom and beneath the second rung 85 25 of the chair back portion, all as shown particularly in Figs. 5 and 6 of the drawings. When thus collapsed the chair folds into a compact substantially flat body, so that a very considerable number thereof may be stood or piled together in a minimum of storage space. 90

From the above description it will be apparent that the novel folding chair of this invention will provide a very strong and yet light weight device adapted for compact reduction in bulk when not in use; it therefore follows that the chair is admirably adapted for service wherever a folding chair is desired, and is especially adapted for undertakers' use, caterers' use and for similar uses 100 in connection with which a light strong chair is desired which is readily portable, and which is so devised that when collapsed a very considerable number thereof may be transported or stored so as to occupy a minimum of space. 105

Another feature of the invention which is of advantage resides in the arrangements provided for mounting and dismounting the seat member 20 and back member 31 from the chair frame, whereby such parts may be easily 110 and quickly removed for cleansing or replacement, all to the end that the chairs may be easily maintained in good appearance as well as functionally efficient.

As many changes could be made in the above described construction and many widely different embodiments of this invention could be made without departing from the scope thereof, it is intended that all matter contained in the above description or shown 120 in the accompanying drawings shall be interpreted as illustrative and not in a limiting sense.

I claim:

1. A folding chair, consisting in a seat portion comprising laterally spaced pairs of front and rear legs in crossed relation and pivotally connected at the junctures of crossing, a pivot rung extending between said pairs of legs, lateral supporting bars secured respec- 130

tively to and between the upper ends of said front legs and the upper ends of said rear legs, a flexible seat member connected with and extending between said supporting bars; 5 a back portion comprising a frame provided with side uprights having their lower ends pivotally and positively attached to the lower portions of said rear legs, a back member supported by said frame, said side uprights of the frame having indented locking notches in their rear marginal portions, and external stop projections at the upper rearward ends of said front legs engageable by said locking notches to interlock said back portion and seat portion together in operative opened out service position.

2. A folding chair, consisting in a seat portion comprising laterally spaced pairs of front and rear legs in crossed relation and 20 pivotally connected at the junctures of crossing, a pivot rung extending between said pairs of legs, footing rungs respectively secured to and between the lower extremities of said front legs and of said rear legs, lateral 25 supporting bars secured respectively to and between the upper ends of said front legs and the upper ends of said rear legs, a flexible seat member connected with and extending between said supporting bars; a back portion 30 comprising a frame provided with side uprights having their lower ends pivotally and positively attached to the lower portions of said rear legs, the pivotal attachment of said back portion with the lower portions of said rear legs being adjustable to provide for 35 selectively varying the angle of inclination of said back portion with respect to said flexible seat as well as to fix the amount of slack in said seat, a back member supported by said frame, said side uprights of the frame having indented locking notches 40 in their rear marginal portions, and external stop projections at the upper rearward ends of said front legs engageable by said locking notches to interlock said back portion and seat portion together in operative opened out service position.

3. A folding chair, consisting in a seat portion comprising laterally spaced pairs of front and rear legs in crossed relation and 45 pivotally connected at the junctures of crossing, a pivot rung extending between said pairs of legs, lateral supporting bars secured respectively to and between the upper ends of said front legs and the upper ends of said rear legs, means for detachably retaining said supporting bars in assembled relation to said legs, a flexible seat member having attachment loops removably engageable over 50 said supporting bars; the lower portions of said rear legs having a plurality of spaced apertures therein, a back portion comprising a frame provided with side uprights having a plurality of spaced apertures in their lower 55 end portions, connecting means arranged for

selectively connecting apertures of said back portion with apertures of said rear legs, whereby the angle of inclination of said back portion with respect to said flexible seat is varied as desired, lateral rungs fixed to and 60 between said side uprights above said seat portion, a removable back member in the form of a sleeve to slide over the upper portion of said frame so as to be continuously supported thereby, said side uprights of the frame having indented locking notches in their rear 65 marginal portions, and external stop projections at the upper rearward ends of said front legs engageable by said locking notches to interlock said back portion and seat portion together in operative opened out service position.

4. A folding chair, consisting in a seat portion comprising laterally spaced pairs of front and apertured rear legs in crossed relation and pivotally connected at the junctures of crossing, a pivot rung extending between said pairs of legs, footing rungs respectively secured to and between the lower extremities of said front legs and of said rear legs, lateral 70 supporting bars secured respectively to and between the upper ends of said front legs and the upper ends of said rear legs, means for detachably retaining said supporting bars in assembled relation to said legs, a 75 flexible seat member having attachment loops removably engageable over said supporting bars; a back portion comprising a frame provided with side uprights having their lower end portions provided with a plurality of 80 apertures, pivot bolts extending through apertures in said back portion and in said rear legs, whereby said back portion is pivotally attached in selected angular positions to the lower portions of said rear legs, lateral rungs 85 fixed to and between said side uprights above said seat portion, a removable back member in the form of a sleeve to slide over the upper portion of said frame so as to be continuously supported thereby, said side uprights of the frame having indented locking notches in their rear 90 marginal portions, and external stop projections at the upper rearward ends of said front legs engageable by said locking notches to interlock said back portion and seat portion together in operative opened out service position.

In testimony that I claim the invention set forth above I have hereunto set my hand this 28th day of August, 1928.

AUGUST GRAMS.
